UNITED STATES PATENT OFFICE.

FREDERICK C. BLANCHARD, OF DORCHESTER, MASSACHUSETTS.

LUBRICATING APPARATUS.

Application filed July 17, 1924. Serial No. 726,517.

This invention aims to improve lubricating apparatus of the class in which a manually operable, portable filler is employed to fill and to replenish from time to time receptacles such as oil cups and oil holes used for motor-car chassis lubrication, and for the lubrication of other machinery of various kinds.

The invention will be best understood by reference to the following description, when taken in connection with the accompanying drawings of one specific embodiment thereof, while its scope will be more particularly pointed out in the appended claims.

In the drawings:

Fig. 1 is an elevation of a lubricating apparatus exemplifying the invention;

Fig. 2 is a plan of a portion of the apparatus illustrated in Fig. 1, on an enlarged scale;

Fig. 3 is a sectional view on line 3—3 of Fig. 2; and

Fig. 4 is a sectional view on an enlarged scale on line 4—4 of Fig. 1.

Referring to the drawings, and to the embodiment of the invention which is selected for exemplification, there is shown in Fig. 1 a lubricating apparatus comprising a filler and a receiver, the filler comprising a reservoir having an outlet conduit leading therefrom, herein exemplified by an oil can presenting a reservoir 5 and a spout 6. The receiver is exemplified by an oil cup presenting a reservoir 7, having an inlet 8 and an outlet 9, the former being normally closed by an appropriate closure, herein a cover 10, which is spring controlled, the cover to that end being secured to a stem 11, which is encircled by a helically coiled compression spring 12, the upper end of which is seated against an appropriate fixed abutment, herein a yoke 13, which spans the inlet, but leaves space for the introduction of lubricant, while the other end of the spring rests against a movable abutment 14 carried by the stem. In the present embodiment, the stem also carries a permeable valve 15 of felt or other appropriate material, which in its normal position is seated against a tapered valve seat 16 between the inlet and outlet, the arrangement being such that when the oil cup and the connections leading to the bearing have been flooded with oil, and the cover and valve closed, the oil remaining in the reservoir gradually seeps through the permeable valve and continues to supply oil in small quantities to the bearing, in the intervals between replenishing operations. The cover and body of the oil cup present abutments 17 and 18 for

cooperation with the cover opening and receptacle filling implements now to be described in detail.

Suitably carried by the filler is an orifice-positioning closure opener, which lifts the cover and opens the valve, positioning an outlet orifice 19 of the spout 6 for delivery of oil into the oil cup. In the present embodiment, this orifice-positioning closure opener comprises a fork presenting two arms 20 (see Fig. 2), adapted to enter the spaces presented by the abutments 17 and 18 at opposite sides of the oil cup, and to embrace the latter, thereby to position the outlet orifice of the spout laterally with relation to the oil cup. By this means, the outlet orifice is positioned horizontally in a direction transversely of the oil cup, and also vertically with respect to the oil cup, the vertical positioning being due to the fact that the spring-pressed cover urges the arms in a downward direction onto the abutment 18 presented by the oil cup. The advance of the filler is limited in a most convenient manner by an abutment 21 presented by the fork, and which brings up against the side of the reservoir, as best shown in Fig. 2.

To facilitate the entrance of the arms of the fork into the spaces presented between the fixed and movable abutments provided on the oil cup, the arms in the present example present wedge-like or tapered formations 22 (see Fig. 1), as viewed in profile, while, as viewed in plan, their extremities herein diverge somewhat, as at 23 (see Fig. 2). When, therefore, the fork is applied to the cup and, thrust forward, the cover is easily lifted, tilted, and pushed somewhat to one side, at the same time lifting the valve. During this movement, the forward end of the spout enters the space between the cover and inlet of the reservoir, and the outlet orifice of the spout is presented in a position directly above and nearly central with respect to the inlet (see Fig. 3). When the parts are in this position, pressure on the bottom of the oil can expels oil from the reservoir through the spout into the oil cup, after which the cover is allowed to close by simply withdrawing the oil can in a rearward direction, the spring asserting itself to restore the cover and the valve to their normal closed position.

It happens that there are many places about motor cars and other machinery which it is not customary to equip with oil cups. Some of these parts have common oil holes, while others have none at all, and in the lat-

ter case, it is usual to apply the tip of the oil can spout at a point where the oil, when expelled, will run between the bearing surfaces. In situations such as these, it is not desirable 5 to use the cover opener, and in fact, in most cases it is desirable, and many times altogether necessary, to have the cover opener out of the way, so that the forward end of the spout will be entirely unobstructed. To 10 these ends, therefore, the cover opener is mounted for movement into a retracted position, by means such as those that are now to be described. In the present embodiment, the cover opener is conveniently advanced and 15 retracted by being pivotally mounted on the oil can spout, so that it may be swung from its normal position shown in full lines in Fig. 1 to the retracted position shown in dotted lines.

20 Herein, the cover opener comprises two plates 24, conveniently secured together as by a rivet 25 extending therethrough, and these plates are formed to present a second fork, herein comprising two arms 26 (see 25 Fig. 2), which embrace a part of the filler, herein a clamping collar 27 disposed about the spout (see Fig. 4). Owing to the usual tapered formation of the spout, ordinary methods of securing the collar to the spout 30 would be unsatisfactory, and I have therefore provided an especially practicable and effective means of attachment, which will now be described.

To provide a positive interlocking connection 35 between the collar and the spout, the latter herein is provided with an indentation 28, conveniently made by squeezing the wall in an inward direction, and this indentation receives a clamping bolt 29, which not only interlocks with the spout, but also serves 40 to urge the sides of the clamping collar toward the spout and to squeeze the latter therebetween, the bolt to that end having at one end a head 30 which rests against one side of 45 the collar, and at its other end a nut 31, which rests against the opposite side of the collar (see Fig. 4). The clamping collar herein is generally U-shaped, and has arms 32 which 50 embrace the oil can spout, the terminal portions of these arms being curved inwardly as at 33, and partially wrapped about the spout. As the spout has a tapered formation, the arms of the clamping collar are correspondingly tapered (see Fig. 2); that is to say, the 55 surfaces which engage the spout are not cylindrical, but are of conical form corresponding to the conical formation of the spout. When these surfaces are forced toward each other by the action of the clamping bolt, the resultant 60 forces on the wall of the spout are in the general directions of the arrows A in Fig. 4, and the spout is thereby crowded against the bolt; that is to say, the bolt is thereby seated all the more firmly in the indentation 65 in the spout.

The head and nut of the bolt present convenient trunnions for the arms 26, the nut to that end in the present example being cylindrical around its periphery, and to enable the nut to be turned when assembling the parts, 70 the nut herein is provided with a slot 34 to receive a special screw-driver which is bifurcated to span the threaded end of the bolt. When the nut has been screwed firmly into place, it is conveniently prevented from turning by heading, or staking the end of the bolt as at 35, thus forcing some of the material of the bolt into the slot in the nut. 75

To hold the cover opener against accidental swinging movement on the trunnions, I have 80 provided spring friction means conveniently presented by the arms 26 themselves, which are resilient and initially separated by a space less than that which they occupy when 85 in place, so that they constantly exert considerable pressure against the parts therebetween, and thus produce sufficient friction to resist accidental swinging movement to a very substantial degree. This resistance is ample to retain the cover opener in any position in which it might be placed, more particularly in its retracted position. While this 90 resistance might be relied upon to hold the cover opener in its advanced position, I prefer to provide locking means definitely to retain the opener in such position in the manner now to be described. 95

Still referring to Fig. 4, one of the arms 26 herein is provided with a shallow depression 36 adapted to receive a protuberance, such as a steel ball 37 mounted on the side of one of the arms 32 of the clamping collar, as by providing the latter arm with a seat 38 of conical formation to receive the ball. By reference to the left-hand side of Fig. 4, it will be observed that this arm 26 is separated from the corresponding portion 32 by a space sufficient to utilize the spring pressure afforded by the arm 26 to urge the ball into the depression when in registration therewith, 100 while permitting the ball to ride out of the depression when sufficient force is applied to the cover opener. When the ball is not in registration with the depression, the ball simply 105 rides along the flat surface of the adjacent face of the arm. Thus I have provided means automatically to position the cover opener definitely in its advanced working position, and to hold the same frictionally 110 against accidental movement when moved from its normal position. This can be accomplished instantly and conveniently, without the use of tools and without loose parts, 115 which might be dropped or lost. 120

Having thus described one embodiment of the invention, but without limiting myself thereto, what I claim and desire by Letters Patent to secure is:

1. In a lubricating apparatus, the combination of a lubricant conduit having a discharge 125

orifice, a closure opener mounted for movement relatively to said conduit from an advanced position adjacent said orifice to a retracted position relatively remote therefrom, and means for causing said opener to remain attached to and supported by said conduit during said movement.

2. An oil receptacle filling device comprising, in combination, a filler having a discharge orifice, orifice positioning means mounted on said filler for movement from a position in which it is adapted for cooperation with an oil receptacle to guide said discharge orifice into proper position with relation to the oil receptacle inlet to a position in which said positioning means is non-operative, and means for causing said positioning means to remain attached to and supported by said filler during said movement.

20 3. An oil receptacle filling device comprising, in combination, a filler having a discharge orifice and orifice-positioning and closure-opening means mounted on said filler for movement from an advanced position in which said means are adapted for cooperation with an oil receptacle to position said discharge orifice with relation to the oil receptacle inlet and to open its closure, to a retracted position in which said means are out of cooperative relationship with said discharge orifice, and means for causing said orifice-positioning and closure-opening means to remain attached to and supported by said filler during said movement.

25 4. An oil receptacle filling device comprising, in combination, a filler having a discharge orifice and an orifice-positioning, closure opener pivoted to said filler to swing laterally with relation to said orifice from an operative position, in which it is adapted to position said orifice and to open the closure of a receptacle, to an inoperative position, and means to cause said opener to remain attached to and supported by said filler during its swinging movement.

5. An oil receptacle filling device comprising, in combination, a filler having a discharge orifice, an orifice-positioning, closure opener mounted on said filler to move relatively to said discharge orifice from an operative position in which it is adapted to position said orifice and to open the closure of a receptacle to an inoperative position, and detent means to hold said opener in said operative position.

6. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, and means to hold said opener in said operative position and in said inoperative position.

65 7. An oil receptacle filling device comprising,

ing, in combination, a filler having a discharge orifice, an orifice-positioning closure opener pivoted to said filler to swing from an operative position in which it is adapted to position said orifice and to open the closure of a receptacle to an inoperative position, and means to retain said opener definitely in said operative position, said means including a device operated by a thrust on said opener to render said means ineffective to hold said opener definitely in said operative position.

8. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, and resiliently yieldable detent means automatically to locate said opener in said operative position.

9. An oil receptacle filling device comprising, in combination, a filler having a discharge orifice, an orifice-positioning, closure-opener pivoted to said filler to swing from an operative position in which it is adapted to position said orifice and to open the closure of a receptacle to an inoperative position, and means automatically to lock said opener in said operative position by merely moving said opener into such position.

10. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, and a spring associated with said opener normally to hold said opener in said operative position.

11. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, and detent means including two interengageable parts and a spring to hold said parts in interengagement to retain said opener in its operative position.

12. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, and detent means including a pair of resilient arms embracing a part of said filler and interengageable parts normally maintained in interengagement by the resiliency of said arms to retain said opener in said operative position.

13. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, said opener presenting a fork comprising two arms to embrace a part of the receptacle to be filled and two arms to embrace a part of said filler, and means cooperating with the second-mentioned arms to retain said opener against accidental movement.

14. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, said opener presenting a fork comprising two arms to embrace a part of the receptacle to be filled and two arms to embrace a part of said filler, and interengaging means cooperating with the second-mentioned arms to retain said opener in a predetermined operative position.

15. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, said opener comprising two plates secured together and presenting a pair of arms to embrace a part of the receptacle to be filled and a pair of arms to embrace a part of said filler, and means cooperating with the second-mentioned pair of arms to retain said opener against accidental movement.

16. An oil receptacle filling device comprising, in combination, a filler having a discharge orifice, an orifice-positioning, closure opener pivoted to said filler to swing

from an operative position in which it is adapted to position said orifice and to open the closure of a receptacle to an inoperative position, said opener comprising two plates secured together and presenting a pair of arms to embrace a part of the receptacle to be filled and a pair of resilient arms to embrace a part of said filler, and means to utilize the resiliency of said arms to retain said opener against accidental movement.

17. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, said opener comprising two plates secured together and presenting a pair of arms to embrace a part of the receptacle to be filled and a pair of resilient arms to embrace a part of said filler, one of said arms presenting a depression, and a protuberance carried by said part of said filler to enter said depression and to retain said opener against accidental movement.

18. An oil receptacle filling device comprising, in combination, a filler having a discharge orifice, an orifice-positioning, closure opener pivoted to said filler to swing from an operative position in which it is adapted to position said orifice and to open the closure of a receptacle to an inoperative position, said opener comprising two plates secured together and presenting a pair of arms to embrace a part of the receptacle to be filled and a pair of resilient arms to embrace a part of said filler, one of said resilient arms presenting a depression, and a ball carried by said part of said filler to enter said depression and to retain said opener against accidental movement.

In testimony whereof, I have signed my name to this specification.

FREDERICK C. BLANCHARD.
